(57) **CLAIM**

The ornamental design for a wood-type head for a golf club, as shown and described.

DESCRIPTION

FIG. 1 is a perspective view showing the front, toe and heel sides of a wood type for a golf club embodying the new design;

FIG. 2 is a front elevational view thereof;

FIG. 3 is a toe side elevational view thereof;

FIG. 4 is a heel side elevational view thereof;

FIG. 5 is a rear elevational view thereof;

FIG. 6 is a top plan view thereof;

FIG. 7 is a bottom plan view thereof;

FIG. 8 is a sectional view taken generally on the line 8—8 of FIG. 3;

FIG. 9 is a bottom plan view of a second embodiment of the golf club head as disclosed in FIG. 1; and,

FIG. 10 is a sectional view of the second embodiment, corresponding generally with the sectional view of FIG. 8. The undisclosed sides of the second embodiment are identical to those shown with respect to the embodiment of FIGS. 1-8.

The broken line showings of a fragmented shaft and striking face is for illustrative purposes only and form no part of the claimed design.
